Application June 17, 1935, Serial No. 26,996

11 Claims. (Cl. 221—47.5)

This invention relates to dispensing apparatus, and with regard to certain more specific features, to tamper-proof, lubricant-dispensing apparatus.

Among the several objects of the invention may be noted the provision of a container for the wholesale distribution of lubricant which shall be non-refillable by the retailer and which may be refillable by the wholesaler; the provision of apparatus of the class described which provides for filling from the wholesale container certain retail containers which are non-refillable except by pumping apparatus which may be fitted to the wholesale container; the provision of pumping apparatus for taking lubricant from the wholesale container and efficiently delivering it to said retail container; the provision of transfer apparatus which is operable only with the wholesale and retail containers above referred to and which has advantageous transfer functions only when used in connection therewith; and the provision of apparatus of the class described which is simple in construction and in operation and which does not require a large investment to be effectively distributed. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side elevation of a filled, wholesale container, parts being shown in section;

Fig. 2 is a side elevation of pumping apparatus adapted to be used in connection with the container of Fig. 1;

Fig. 3 is a perspective view showing a grease-gun and retail container;

Fig. 4 is a fragmentary section of the parts of Fig. 3 when assembled;

Fig. 5 is a perspective of a release plug shown in Fig. 4;

Fig. 6 is a side elevation of an alternative form of outlet for the gun shown in Fig. 3;

Fig. 7 is a complete vertical section of the wholesale container, pump and retail container assembled for transfer of lubricant from the former into the latter, and showing the wholesale container about half empty;

Fig. 8 is a cross section taken on line 8—8 of Fig. 7;

Fig. 9 is a section taken on line 9—9 of Fig. 8;

Fig. 10 is a side view illustrating the operation of the apparatus;

Fig. 11 is a view similar to Fig. 7 showing a washing attachment; and,

Fig. 12 is a view similar to Fig. 7 showing a filling attachment.

Similar reference characters indicate corresponding parts throughout the several views of the drawings.

We have found it to be desirable to have (1) the wholesale distribution of lubricants in authorized tamper-proof containers which are non-refillable, except at the source of supply and, (2) the facility for easy transfer of the lubricant from such container only to authorized cartridges and grease guns or the like from which the lubricant is ultimately retailed, said cartridges being also non-refillable, except from said wholesale container. It is desirable that the tamper-proof and non-refillable characteristics of the containers be made an aid, rather than a hindrance to the activities of the retailer in distributing lubricant therefrom. It is furthermore desirable that the transfer of lubricant from the wholesale containers to the retail containers be effected with a minimum possibility of adulteration and inadvertent entry of foreign materials such as dirt, grit and the like. The filling operation itself should be easily carried out per se, and only with the transfer apparatus that applies to the wholesale container, so that the retail container can only be filled with lubricant from the wholesale container, whereby the wholesaler may control the quality of the lubricant from the time it leaves the refinery until the time it reaches the ultimate customers.

Referring now more particularly to Fig. 1, there is shown at numeral 1 a sheet metal container of substantial gauge. The manner of filling this container will be described later. As indicated at numeral 3 in Fig. 1, the container is substantially full of lubricant, which may be liquid, semi-liquid, or semi-solid, and resting on the top of the lubricant 3 is a free piston 5 which has a sliding but not tight contact at 7 with the side walls of the container 1, and which is provided at its center with a bushing 9 having an opening 11 therethrough surrounded by a flat raised and machined seat 13. The bushing is preferably pressed into the piston 5.

The container 1 carries a permanent top 15 having a central opening into which is rolled and sealed a bushing 17. The bushings 9 and 17 carry threads 19 and 21 which respectively are of the same pitch. The threads 21 are adapted to

be threadably engaged by the head 23 of a closure cap 25. The cap 25 has a wrench-engaging extension 27 carrying outside threads for engaging the threads 19 on the inner bushing 9. 5
5 A light sheet metal seal 28 is pressed over and around the bushing 17 to provide means whereby any attempt to tamper with the cap 25 may be detected. Suitable sealing compounds are used between the flange 17 and top 15, the flange 17 and cap 25, and between the flange 17 and the seal 28. 10
10

In order to open the drum or container 1, the seal 28 is broken and the cap 25 revolved by applying a tool to the wrench-engaging interior thereof shown at numeral 21. The removal of the cap 25 unthreads it from the bushing 17 and from the bushing 9. This presents an opening through the bushing 17 for threadably applying the pump assembly (shown in Fig. 2) to the threads of the bushing 9. 15
15

The pump assembly as shown at Fig. 2 comprises a tubular cylinder 33 carrying a threaded bushing 35 at the lower end. The threads of the bushing 35 cooperate with those of said bushing 9 of the floating pistons 5. The bushing 35 is affixed to the cylinder 33 and has an enlarged cylindric chamber 39 therein at the end of which is a spring retainer 41 for retaining in the cylindric portion 39 a foot valve 43 (Fig. 7). The valve 43 comprises a flat central portion for seating on the seat 13 and has upstanding spaced legs 45 which limit the opening movement of the valve by contact with a shoulder 47 and which are flared as shown at 49 to limit the 20
20 downward movement of the valve by contact with the retainer 41 when the bushing 35 is unscrewed from the bushing 9. This form of valve constitutes an advantageous feature of the invention because, when the pump is removed from the wholesale container, one seating element of the valve is removed and it is only this form of element that will properly make a seal on the seat 13. This means that only the particular 25
25 design of valve is useful with the bushing 9 and since this valve is special in the pumps furnished, only these pumps are useful.

Slidably carried on the outside of the cylinder 33 is a guide bushing 51 which is threaded into the bushing 17 to form a guide for sliding movement of the cylinder therethrough after the lower bushing 35 has been threaded into the piston bushing 9. Thus the pump cylinder 33 may descend with the follower piston 5 as lubricant is withdrawn from the container 1, as suggested in Fig. 7. Enough air leaks in between the cylinder 33 and bushing 51 to provide atmospheric pressure on the follower 5. 30
30

In order that the threading operation between bushings 35 and 9 may be carried on in the filled condition of the container as shown in Fig. 1, an ear 53 is struck up from the follower 5 and is adapted to cooperate with an ear 55 struck down from the top 15. Also, an ear 57 is struck down from the follower 5 is adapted to cooperate with an ear 59 struck up from the bottom of the container 1 when the follower has descended and the container has been emptied. Thus the ears 55 and 53 permit positive initial application of the cylinder to the follower and the ears 57 and 59 permit positive ultimate removal thereof. 35
35

Within the cylinder 33 is a piston rod 61 which passes outwardly through a stuffing gland 65 in a head 63. At the lower end of the rod 61 is a reduced portion 67 carrying a valve seat 69 with which cooperates a corresponding seat 71

in a loose piston 73. The loose piston 73 can move from the position shown in Fig. 7 downwardly to a position wherein the seats 69 and 71 contact. Packing 75 prevents leakage around the piston. The piston 73 is hollow permitting 5
5 flow of lubricant therethrough upon the downward stroke of the piston rod 61. Upon the upward stroke, the piston seats on the member 69 so as to seal off the lubricant which upon the down-stroke has passed to a position above the 10
10 piston.

The piston rod 61 is reciprocated by means of an oscillating handle 77 pivoted to a link 79, the latter in turn being pivoted to said head 63. 15
15

From the above it will be seen that by oscillating the handle 77, lubricant may be withdrawn from below the follower 5 and forced through the cylinder 33 to an outlet 81 in the head 63. The outlet 81 has threaded thereto an extension 83 which has formed therein a seat 85 with which 20
20 cooperates a ball check 87 normally pressed to the seat 85 by a spring 89. When pressed to its seat, the ball 87 contacts with the inner end 91 of a T-shaped member, the outer end 93 of which is thus normally pushed outwardly. Thus the 25
25 outlet 81 is automatically shut when the pump is not connected with a cartridge to be described. The T head 91 prevents the member 93 from being pushed entirely out when the ball 87 seats. The member 93, as shown in Fig. 8, is not round 30
30 but flat, so that when the ball check valve 87 is open, lubricant may flow out around the member 93.

Around the extension 83 is a coupling nut 95 within which is carried a packing 97. The coupling nut 95 is adapted to threadably cooperate with the outlet 99 of a cylindric retailing container or cartridge 101 which forms an attachment for the grease gun illustrated in Fig. 3. The outlet 99 is adapted to thread, either with 40
40 said coupler 95 of the pump, or with the inlet bushing 103 of a gun head 105 having a pump mechanism 107 and a coupler outlet 109 whereby lubricant may be withdrawn from the cartridge 101 and compressed from the coupler outlet 109. 45
45 In this connection it may be noted that the coupler outlet 109 may be removed and an extension 111, shown in Fig. 6, applied. Other types of extensions may also be used. It will be understood that only one or at most, a few pumps 105 are 50
50 required, for which an assortment of outlets 109, 111 or the like are carried, and an assortment of cartridges 101. The cartridges 101 are filled from their respective wholesale containers in the manner herein described and may be selectively applied to the pumps 105 so that various lubricants may be retailed for various purposes direct to the 55
55 bearings of the motor cars or the like of the ultimate purchasers of the lubricant.

As shown in Fig. 7, the cartridge 101 has an 60
60 internal, rolled flange 113 which forms a limiting stop for a follower piston 115. The piston 115 is normally forced inwardly into the cartridge 101 by a spring 117 which reacts in an enclosed head 119 forced into permanent position on the 65
65 cartridge 101. The head 119 is not removable from the cartridge so that the spring 117 and piston 115 can never be reached by the retailer. During operation of the pump 105, while the cartridge is threaded thereto, the piston 115 under pressure of the spring 117 functions to maintain the retail supply of lubricant in the cartridge 101 under a super-atmospheric pressure so as to maintain the prime of the pump gun 105. At 70
70 75

this time, a bushing 2 (Figs. 4 and 5) having a stem 4 and permanently positioned in the inlet 103 maintains the outlet check valve 121 open, the latter being located in the outlet of the cartridge 101. The bushing 2 has holes 6 therein permitting flow therethrough when the cartridge 101 is attached to the pump gun 105. The valve 121 automatically opens when the cartridge and gun are assembled (Fig. 4) and automatically closes when they are separated (Fig. 3). After the contents of the cartridge 101 have been completely ejected by the pump 105, the piston 115 is adjacent to the head 99.

In order to fill the cartridge 101, the threaded nozzle 99 thereof is threaded into the coupler 95 at the outlet of cylinder 33, the gaskets 97 functioning as a seal between said nipple 99 and the outlet member 83. This operation causes the flanged end 8, (Fig. 9) of the outlet 99 to contact the end of the member 93, so that the latter is forced back into the outlet 81, thus unseating the ball check valve 87. Thus, when the cartridge 101 is fastened at the outlet member 83, valve 87 automatically opens.

Then, as shown in Fig. 10, the operator grasps with one hand the cartridge 101 which functions as a handle and oscillates the lever 77 with his other hand, thus pumping lubricant from beneath the follower 5, through the cylinder 33, through the outlet 81 and open check valve 87 to the cartridge 101. The lubricant under pressure, automatically opens the check valve 121 in the cartridge 101 and flows against the piston 115, displacing the same toward the head 119 and at the same time storing energy in the spring 117. The final filled position of the piston 115 in the cartridge 101 is that shown in Fig. 7.

It will be seen from Fig. 10 that the forcing stroke of the handle 77 is a downward one so that the pressure exerted by the operator on the follower 5 aids the atmospheric pressure thereon to prime lubricant into the cylinder 33. On the suction stroke, when the handle 77 is pulled up, the other hand on the cartridge 101 may be used 45 to react downwardly to prevent lifting up of the drum 1. This reaction is not high because it amounts only to the frictional force required to drive the piston 73 and associated parts through the lubricant in cylinder 33 plus the friction of 50 the rod 61, minus the force of gravity on the apparatus as a whole.

After the cartridge 101 has been filled, as will be known by the increased resistance to pumping, it may be unscrewed. The flange 8 of outlet 99 leaves contact with the member 93 so that the outlet check valve 87 automatically closes. At the same time, or theretofore, the outlet check valve 121 in the cartridge 101 also automatically closes. The cartridge 101 is then uncoupled and applied to the pump 105, as described. The pump 105, carrying the cartridge 101 is then used to deliver the lubricant to suitable lubricant-receiving fittings or the like in communication with the bearings to be lubricated.

After the lubricant below the follower 5 has been exhausted, by repeated fillings of cartridges 101, the pump cylinder 33 may have its bushing 35 unscrewed from the bushing 9 and the guide bushing 51 is unthreaded from the bushing 17. The cap 25 is then reapplied to the container and it is shipped back to the wholesaler for a re-filling, while the retailer applies the pump cylinder 33 to another wholesale container which he has available. The wholesaler, having the container returned proceeds as follows:

A guide tube 131 (Fig. 11) having a coupling 133 for application to an inlet conduit 135 is screwed into the bushing 9. A pressure nozzle 137 on the end of the conduit 135 is passed through the guide tube 131 and through the hole 5 in the bushing 9. At its lower end the pressure nozzle 137 is provided with jets 139 and an open end 141. An opening is formed in the container by pushing out of position a plug 143. This plug is renewable only by special rolling tools, and therefore is not useful to the retailer for unauthorized refilling purposes.

The coupling 133 is detachable so that the guide 131 may be screwed to the bushing 9 before application of the pressure nozzle 137. The nozzle 15 is then inserted into the tube 131 and the latter attached to the conduit 135. The relationship between the length of a tube 131 and pressure nozzle 137 is such that the follower 5 is raised when the said assembly is made. The follower is 20 thereby held in an upward position while steam or other washing solution is forced through the jets 139 against the inside walls of the container. Drainage takes place through the hole left by removal of the plug 143.

When the washing operation has been completed, the coupling 133 is broken, and the conduit 135 with the nozzle 137 lifted, after which the guide tube 131 is disconnected from the bushing 9. Final drainage of the washing fluid is 30 completed and thereafter a new plug 143 is pressed and/or rolled into position.

After drying, and as shown in Fig. 12, a lubricant filler is applied. This comprises another guide tube 145 having a detachable coupling 35 means 147 with a lubricant conduit 149. The conduit 149 carries a lubricant filling nozzle 151 through which passes a stem 153 normally biased downwardly by a spring 155 and adapted to be drawn upwardly through stuffing gland 157 by means of a rocker handle 159. The stem 153 carries at its lower end a closure member 161 for supporting a packing 163 which engages said seat 13 in the bushing 9. It also carries a nozzle 165 which cooperates with a valve 167 on the lower end of the stem 153. The nozzle 165 also confines the packing 163.

A filling operation is accomplished by first screwing the lower end of the guide tube 145 into the bushing 9; then inserting the nozzle 151 through the guide tube so that the outlet 165 is positioned in the hole of bushing 9. The coupling 147 is then made fast, thus clamping gasket 163 against seat 13 and the valve 167 opened, whereupon lubricant flows in from the conduit 149, through the nozzle 151, open valve 167, outlet 165, bushing 9, to a point beneath the piston 5. As the lubricant flows in, the piston rises until it reaches its uppermost position shown in Fig. 1. The tube 145 is then disconnected at the coupling 147, the nozzle 151 removed, and then the tube 145 is unscrewed from the bushing 9 and the cover and seal applied as shown in Fig. 1. Air escapes from above the piston 5 between the guide tube 145 and bushing 146.

Among the advantages of the invention are 65 the following:

1. The lubricant is never exposed to contamination from the time it leaves the wholesaler until the time that it is positioned in the ultimate 70 customer's bearing.
2. Cooperating elements 43 and 13 of the valve in the bushing 35 of the pump are separated when the pump is disconnected from the wholesale container. Only the forms of cooperating valve 75

parts designed for cooperative action will function properly, and therefore it is practically certain that the user of the pump will not use it for pumping other lubricants from other sources.

5. 3. Without special tools, which only the wholesaler has, it is impossible to refill the wholesale container with any profit to the one who would refill it.

4. Inasmuch as the cartridge 101 is designed particularly for connection with the specific pump herein described, it is, as a practical proposition, also difficult to refill it with other lubricants. This is because of the ball check valve 121, and the fact that the piston 115 cannot be removed rearwardly for filling in the lubricant by the use of a paddle.

5. The outlet check valve on the pump prevents dispensing from the wholesale container to any other containers except the cartridges described herein.

6. The wholesale containers may be used repeatedly and therefore the cost per unit of lubricant delivered is reduced to a reasonable amount.

7. The authorized refilling of both the wholesale and retail containers is easily accomplished.

8. The retail cartridge and grease gun assembly are small and compact so that relatively inaccessible fittings may be reached for servicing.

9. The pump 33 cannot be operated for filling other unauthorized containers without excessive trouble.

In view of the above, it will be seen that the several objects of the invention are achieved and other advantageous results attained.

35. As many changes could be made in carrying out the above constructions without departing from the scope of the invention, it is intended that all matter contained in the above description or shown in the accompanying drawings shall be interpreted as illustrative and not in a limiting sense.

We claim:

1. In lubricating apparatus, a container for lubricants, a head on said container, a follower in said container between the lubricant and said head, a pump, said head having an opening for introduction of a portion of said pump into the container, means for detachably fastening said pump to said follower, said follower having an opening whereby said lubricant may be withdrawn from beneath said follower and ejected from the container by operation of said pump, a valve in said pump adjacent the point of fastening to the follower, said valve being removable with the pump, and a seat in the follower adapted to cooperate with the valve when the pump is fastened to the follower.

2. In lubricating apparatus, a container for lubricants, a head on said container, a follower in the container, a cap, said head having a threaded opening for said cap, said follower having a threaded opening, said cap having threads of pitch to simultaneously thread into said opening in the head and into the opening in the follower when the latter is adjacent the head and the container is full.

3. In lubricating apparatus, a container for lubricants, a head on said container, a follower in said container between the lubricant and said head, said head having an opening, said follower also having an opening, a closure adapted at the same time to be attached to the opening in the head for purpose of closure and to the follower to hold the same adjacent to the head, and means positively maintaining the

follower against substantial rotation with respect to the head when in position adjacent said head.

4. In lubricating apparatus, a container for lubricants, a head on said container, a follower in said container between the lubricant and said head, said head having an opening, said follower also having an opening, a closure adapted at the same time to be attached to the opening in the head for purpose of closure and to the follower to hold the same adjacent to the head, means positively holding the follower against substantial rotation with respect to the head when in position adjacent said head, a bottom in said container, and means positively holding the follower against substantial rotation with respect to the bottom when in position adjacent said bottom.

5. In lubricating apparatus, a container for lubricants, a head on said container having an opening therein, a follower within said container between the lubricant and said head, said follower also having an opening therein in alignment with said opening in the head, a suction pump adapted to be introduced through said opening in the head, fastening means on said suction pump for effecting a detachable connection with said follower, said pump having an outlet, said pump comprising a cylinder, a foot valve, an outlet valve, a valved piston permitting flow only from the foot valve to said outlet valve, and an operating linkage adapted to apply mechanical pressure to the follower to compress the lubricant upon driving a charge ahead of the piston while sucking in a charge beneath the piston.

6. In lubricating apparatus, a container for lubricants, a head on said container having an opening therein, a follower within said container between the lubricant and said head, said follower also having an opening therein in alignment with said opening in the head, a suction pump adapted to be introduced through said opening in the head, fastening means at the base of said suction pump for effecting a detachable connection with said follower, a vertically oscillable handle actuating the pump, said pump having an outlet, said pump comprising a cylinder, a foot valve therein, a valved piston adapted upon rising to pass lubricant only from the foot valve to the outlet and upon descending to pass through lubricant above the foot valve, a linkage connecting said handle and valved piston arranged so that a downward pressure on the handle drives up the piston and applies normal pressure to the follower.

7. In lubricating apparatus, a container, a pump, a member associated with said container and having an opening for withdrawal of lubricant, means on said member adjacent said opening for detachably fastening said pump, an intake valve member in said pump adjacent its point of fastening with said member, and a valve seat on said member cooperating with said valve member when the pump is attached, the valve member and seat separating when the pump is detached, and means associated with the pump for retaining said valve member upon detachment.

8. In lubricating apparatus, a container for lubricants, a head on said container, a follower in the container, a cap, said head having a threaded opening for said cap and said follower having a threaded opening, the threads in the head being of larger diameter than the threads in the follower, and sets of threads on the cap respectively engaging the threads in the head and follower but all having the same pitch.

9. In lubricating apparatus, a container for lubricants, a head on said container, a follower in the container, a cap, said head having a threaded opening for said cap, said follower having a threaded opening, said cap having threads of pitch to simultaneously thread into said opening in the head and into the opening in the follower when the latter is adjacent the head and the container is full, and means preventing relative rotation of the follower with respect to said head when the cap is threaded with respect thereto.
10. In lubricating apparatus, a container for lubricants, a head on said container having an opening therethrough, a follower in said container movable from end to end of the container, a pump adapted to be introduced through said opening and detachably fastened to said follower by rotative movement, a bottom in said container, and means for holding the follower relatively to the container when adjacent either the

head or the bottom, whereby said pump may be attached or detached to the follower by relative rotation when the follower is at either end of the container.

11. In lubricating apparatus, a container for lubricant, a follower on the lubricant, said follower having an opening, a pump attached to the follower and communicating with said opening, valve means associated with said pump, said pump withdrawing lubricant from said follower and delivering it exteriorly of the container, the valve means being arranged so that the delivery and priming strokes of said pump are contemporaneous, actuating means for the pump adapted upon actuation to effect a delivery stroke to apply manual pressure to the follower whereby delivery pressure may be engendered to overcome exterior resistance and to effect a pump priming pressure greater than atmospheric.

FRANK S. BARKS. 20
